Primary Examiner — Darcey E Gottschalk*(74) Attorney, Agent, or Firm* — Themis Law(57) **CLAIM**

The ornamental design for a strap, as shown and described.

DESCRIPTION

FIG. 1 is a perspective view of a strap showing my new design;

FIG. 2 is a front elevational view thereof;

FIG. 3 is a rear elevational view thereof;

FIG. 4 is a right elevational view thereof, the left elevational view being a mirror image; and,

FIG. 5 is a top plan view thereof.

In the drawings, the broken lines depict portions of a strap and environment that form no part of the claim.

1 Claim, 5 Drawing Sheets(56)
